UNITED STATES PATENT OFFICE

2,691,513

MINING APPARATUS WITH CLEANUP

Kenton Eugene McElhattan, Franklin, Pa., assignor to Joy Manufacturing Company, Pittsburgh, Pa., a corporation of Pennsylvania

Application July 2, 1949, Serial No. 102,796

11 Claims. (Cl. 262—29)

1

My invention relates to mining apparatus, and more particularly to mining apparatus of the so-called "continuous miner" type.

Continuous miners are apparatus for mining coal or other mineral from seams or veins in a relatively continuous process, effecting a disintegration of the seam or vein and the removal of the coal or other mineral detached from the seam or vein and delivering it to a transport system, all without intervening handling by man-power.

In a form of continuous miner which has recently come upon the market there is incorporated a tractor-supported base upon which a turntable is mounted for rotation upon a vertical axis. This turntable has on it means for disintegrating a mineral vein, means for receiving the material detached from the mineral vein and carrying it backward, and means for delivering the material so carried backward, to a transport system, such as one or more shuttle cars, a shaker conveyor or the like. The disintegrating mechanism includes, in the apparatus mentioned, a frame which is reciprocable radially of the base along different angularly related generally horizontal paths and a disintegrating apparatus per se mounted on said frame for swinging movement about a horizontal axis perpendicular to the path of reciprocation. This disintegrating apparatus includes a plurality of series of orbitally moving disintegrating elements traveling in similar elongated orbits and so spaced as to tear loose the mineral which they attack over a substantial width—on the order, say, of two to three feet. The disintegrating apparatus is swingable upwardly at its forward end about the horizontal axis mentioned and may be dumped and withdrawn, and may be driven by power provided by motor means so supported as to be rotated upon rotation of the turntable, and so connected with the disintegrating apparatus that the dumping and withdrawing movements of the latter and the vertical swinging movements of the latter will not interrupt the drive of the disintegrating elements. The disintegrating apparatus is provided with hydraulic feeding and retracting cylinders and with hydraulic upswing cylinders, and a cycle of operation applied to a single vertical band of coal or other mineral includes, desirably, a dumping, entering attack on the coal or other mineral, a vertical upswing movement during which usually the largest part of the coal in a particular band is torn loose from the face, and finally a retractive movement during which a roof generally parallel to the mine

2

floor is formed. The coal or other mineral is torn from the face and disintegrated, and most of it is carried by the disintegrating elements rearwardly along the top of the disintegrating mechanism and delivered to a front receiving conveyor which conveys it back to a hopper, in the well known form of apparatus mentioned, from which hopper the material is delivered to a desired discharge point by a rear conveyor. 10 Successive vertical bands are removed across a face until the full width has been covered, and then another layer, so to speak, is progressively mined out by the disintegration of its constituent vertical bands.

15 These machines, when operating in many coal mines, need clamp cleanup devices, because bug dust and some lumps, instead of being discharged to the delivery point of the machine, reach the mine floor in substantial quantity. 20 This need may, of course, exist in the mining of other minerals. Some coal may escape at the partially open side of the upright bands undergoing disintegration; some is detached with such force that it is thrown or bounces out 25 of the front receiving conveyor, and some escapes downwardly through the spaces between the disintegrating elements as these are sweeping through the generally upwardly directed arcuate portions of their travel at the forward end of the disintegrating apparatus. In any event, 30 enough coal—mostly fines—escapes to the mine floor to present a number of problems or complications which make the cleaning up of the bottom both desirable and worth while. While the fine material on the floor is more expensive 35 to clean than the average material that goes over the miner conveyors, it is of real value, and unless it is loaded and taken out of the mine it represents a definite loss.

40 Such material increases fire and dust explosion hazards, and it is difficult and expensive to attempt by rock dusting to obviate these dangers.

A layer of loose material on the floor interferes with setting props, as the coal has to be shoveled aside so the props can be firmly supported on the floor. And the coal displaced in setting props may, since it is likely to be shoveled in front of the operator, not only add to the discomfort of the operator, but actually make things more unsafe for him in the event quick movement may be necessary.

45 From the standpoint of actual operation of the miner, if the bug dust be not removed, there will be more frequent need for adjustment of the lower limit of the disintegrating apparatus, 50 as the level of the surface over which the ma-

55

chine moves will change with the thickness of the unremoved layer of coal. There will be a less stable foundation for the machine as it attacks the face; and, especially in low seams, it may be impracticable to use machines which could otherwise have been employed.

For all these, and perhaps other, reasons, it is highly desirable that provision be made to clean up the loose coal or other material from the mine bottom and effect its delivery with the other and main portions of the disintegrated product.

An object of the present invention is to provide an improved mining apparatus. Another object of the invention is to provide an improved mining apparatus including improved means for effecting the cleaning up from the mine floor of any material detached from a seam or vein and which may escape to the mine floor. A further object of my invention is to provide an improved mechanism for moving loose coal or other disintegrated mineral on a mine bottom into the range of operation of an apparatus which will pick it up from the floor and deliver it to a desired point. Still another object of my invention is to provide an improved floor-cleaning arrangement including a loose material-pushing apparatus operatively connected with a moving part of a mining apparatus for actuation by the latter. A further object is to provide an improved mining apparatus in which a loose material-pushing apparatus is operatively connected with the vein-attacking apparatus of the mining apparatus in such a manner and by such means as not only to move the material of which it changes the position on the mine floor, into the reach of the vein-attacking apparatus, but also as to be moved out of possible interference with the vein-attacking apparatus as the vein-attacking apparatus is moved in a direction to increase its proximity to the loose material-pushing apparatus. A further object of the invention is to provide an improved adjustable material moving apparatus. Yet a further object of the invention is to provide an improved disintegrating and floor cleaning arrangement for a mining apparatus including a disintegrating structure, a structure for moving loose material on the mine bottom within the reach of the disintegrating structure, and an improved interconnecting linkage for coordinating the relative movements of the two structures. Other objects and advantages of the invention will hereinafter more fully appear.

In the accompanying drawings, in which one illustrative embodiment which the invention may assume in practice is shown for purposes of illustration,

Figs. 1 and 2 are, respectively, top plan and side elevational views of the forward end of a continuous miner in which my invention from its various aspects is incorporated.

Fig. 3 is an enlarged fragmentary vertical section on the plane of the line 3—3 of Fig. 1.

Fig. 4 is a sectional view approximately on the plane of the line 4—4 of Fig. 3 but on a reduced scale.

Fig. 5 is an enlarged vertical sectional view on the plane of the line 5—5 of Fig. 4.

Fig. 6 is an enlarged transverse fragmentary sectional view on the plane of the line 6—6 of Fig. 5.

Fig. 7 is a fragmentary side elevational view, corresponding to approximately the right hand half of Fig. 2, showing the floor cleaning apparatus in transport position.

Fig. 8 shows the structure of Fig. 7 in a differ-

ent position, the disintegrating apparatus being shown in a position which it would not ordinarily assume in practice, this position being illustrated only for the purpose of showing the maximum downward movement possible for the disintegrating apparatus.

Fig. 9 is a similar view showing the disintegrating apparatus in elevated position and about to make a withdrawal movement.

Fig. 10 is a similar view showing the disintegrating apparatus about to start a sumping operation, and with the small amount of residual material on the mine floor in the position to which it had been previously moved forward by the pusher mechanism forming a portion of the invention.

Fig. 11 is a view showing a portion of the hydraulic system of the apparatus.

Referring to the drawings, and first to Figs. 1, 2 and 3 thereof, it will be observed that I have shown at 1 a mining apparatus of the so-called continuous miner type. This includes a base 2 adapted to be transported by power driven tractor tread devices 3 and carrying a turntable 4 which may be rotated on a vertical axis 5 by a horizontally rotative force applying means 6. The turntable 4 carries a pair of motors 7, 7 in stationary relation to it, and has guideways 8, 8 in which there is reciprocable, radially of the turntable, a frame 9 which pivotally supports, for swinging movement in vertical planes about a transverse axis 10, a disintegrating mechanism 11, which includes a plurality of disintegrating elements 12, herein shown as supported by circulating chains 13 guided for movement in closed orbits on a built-up bar structure 14 (see Fig. 3). The chains 13 are driven by sprockets 16 carried by a splined shaft 17, which is driven by gearing (not shown) housed in gear boxes 18 supported by the sliding frame 9, power being delivered to the gearing in these gear boxes by telescopic shafts 20 driven by the motors 7. The disintegrating apparatus discharges to a front conveyor 22 of the flight type, and this conveyor is driven from one of the motors 7 through extensible transmission mechanism 23. The front conveyor 22 discharges into a hopper 24 from which a suitable delivery conveyor 25, of which only the forward portion is shown, delivers the material to a desired point rearwardly of the apparatus.

The disintegrating apparatus 11 is adapted to be swung vertically by power supplied by a pair of upswing cylinder and piston mechanisms 27 secured, as at 28, to the bottom of the reciprocable frame 9, and the frame 14 has at its opposite sides depending, rearwardly extending arms 29 pivotally connected at their inner ends, as at 30, to pitmans 31 secured to the pistons 32 of the cylinder and piston mechanisms 27, and adapted to be moved forwardly by hydraulic fluid supplied under suitable control, and to be returned, upon venting of the fluid, by the weight of the disintegrating apparatus.

As so far described, the apparatus is essentially the same as that disclosed in the John R. Sibley application, Serial No. 47,422, filed September 2, 1948 which, following the filing of a continuation-in-part application, Serial No. 102,996 on July 5, 1949, has now become abandoned, the John R. Sibley application and this application having a common assignee. It is believed unnecessary to show and describe the structure thus briefly adverted to in any more detail, but if further description is desired, it may be had by ref-

erence to the patent which will be granted upon the said Sibley continuation-in-part application.

The reciprocable frame 9 includes a material receiving trough structure 40 at whose bottom there is arranged a forwardly sloping deck plate 41 over which the flights 42 of the front conveyor 22 move rearwardly; the return run of this conveyor passes over a lower deck plate 43. The trough structure 40 supports a transversely extending idler roller 45 for the front conveyor 22; and, pivotally supported on the trough structure 40 for swinging about a horizontal axis in the same straight line with the axis of the idler roller 45, which axis is indicated at 46, there is a frame 47 including a pair of rearwardly extending ear elements 48, a transverse plate element 49, forwardly extending side plate elements 50, bottom reinforcing structure 51, and a top plate 52 having its forward portion 53 more steeply forwardly inclined than its rearward portion 54. This suitably reinforced structure carries a rearwardly projecting portion 56, between the ears 57 on which there extends a pin 58 to which there is suitably pivotally connected at 59 the piston rod 60 of a tilt cylinder and piston mechanism 61 supported at its other end, as at 62, on ear structure 63 depending from the bottom deck plate 43. The cylinder and piston mechanism 61 is single acting, and the admission of fluid to its rearward end swings the forward end of the structure 47 upwardly about the axis 46.

The side plates 50 have suitably secured to them gibs 65 spaced apart one above the other, there being a pair of gibs at either side of the structure 47. Suitably slotted guide bars 66 are reciprocable between the gibs and guided by them for longitudinal reciprocation. These guide bars are attached at their forwards ends, herein through an angle plate member 70, to a relatively wide pusher element 71 of boxlike construction and having a forward sloping pusher wall 72. The connection between the pusher structure 71 and the guide bars 66 is herein shown as a rigid one, but it will be readily understood that a structure which would permit the pusher element 71 to swing upwardly as it was retracted, so that it might pass easily over any material that might be behind it, might readily be adopted. All that would be necessary would be to provide a pivotal connection between the forward edge of the horizontal portion of the angle 70 and the top of the pusher structure 71 and to remove the bolted connections between the pusher structure and this angle which are shown in the present drawing.

It will also be noted that if fluid under pressure is not being supplied to the cylinder and piston mechanism 61 the resistance encountered by the heel of the pusher element 71 may kick the structure 47 upwardly and allow the pusher element to pass over any material on the mine bottom or floor, particularly if the rearward side of the pusher element be suitably beveled.

It is desirable that the pusher element 71 be advanced at a time when the disintegrating apparatus cannot have its disintegrating elements snag the pusher structure. It is also desirable that means be provided for pushing the pusher element 71 forward in every position of attack of the disintegrating mechanism across the face, thus causing the pusher element to clear the mine floor within its path of movement and to move any loose material within its path of travel forwardly into a position where it will be picked up by the lower, forwardly moving runs of the dis-

integrating chains 13 and carried up around the forward end of the orbits of these chains and then rearwardly along the tops of the chains, and be discharged onto the conveyor 22 and thus be carried off to a desired point of delivery.

These desirable results are accomplished by arranging appropriate connections between the disintegrating apparatus 11 and the pusher mechanism whereby during upswing of the disintegrating apparatus the pusher mechanism will be advanced and during downswing of the disintegrating apparatus the pusher element 71 will be retracted. This is accomplished by the provision of rigid rearward extension bars 75 welded or otherwise suitably connected to the arms 29, and pivotally connecting these rearward extension arms, as at 76, to forwardly extending links 77 whose forward ends are pivotally connected, as at 78, with ears 79, fixedly secured to the tops of the guide bars 66 near the forward ends of the latter. In this arrangement it will be appreciated at once that as the disintegrating apparatus 11 is swung upwardly the points 76 will be swung in an arc of relatively flat curvature from a point to the rear of a vertical transverse plane including the axis 10, to another point forwardly of such plane, the distance of these points apart being sufficient to provide the desired forward movement of the pusher element 71. Correspondingly, on down swing of the disintegrating apparatus 11, the pivotal connection 76 will be swung rearwardly from a position well forward of the axis 10, as illustrated for example in Fig. 9, to a position to the rear of the vertical plane mentioned, and thus retract the bars 66 through a relatively long stroke.

The mode of operation of the clean-up apparatus will be readily understood from what has been stated. Fig. 10 shows the disintegrating apparatus about to be dumped into a vein as the first step in the removal of a vertical band of material therefrom. It will be noted that there was brought into the reach of the disintegrating elements 12 a substantial heap of bug dust through the preceding forward movement of the pusher element 71. This is largely removed as the disintegrating apparatus, with its disintegrating elements moving orbitally, is lowered into dumping position. As a dumping operation takes place, the pusher element remains on the mine bottom but is advanced with the disintegrating apparatus and will push ahead of it any material it encounters. As the disintegrating apparatus starts its upward movement and material either drops between the disintegrating elements, or for other reasons falls downwardly, this material, plus any other material which has fallen within the path of forward movement of the pusher element 71, will be thrust forward into a position where it may be cleaned up by the disintegrating apparatus when the latter again removes a segment of mineral in the same general relation to the center line of the room or entry. As the disintegrating apparatus 11 moves up, the pivotal connection 76 moves forward, thrusting the links 77 forward and thereby thrusting the bars 66 and the pusher element 71 forwardly. At the end of the upswing movement, as represented in Fig. 9, the pusher element 71 has moved as far forwardly as is possible relative to the then stationary base 2 of the apparatus as a whole. As the withdrawing movement of the disintegrating apparatus takes place and as the disintegrating mechanism is swung back down, after the withdrawing movement has

been completed, the pusher element will be retracted, first due to the retractive movement of the frame 9 and then due to the rearward movement of the bars 66 under the pull of the links 71. It will thus be seen that each time the disintegrating mechanism is dumped in, the pusher element 71 will be advanced concurrently and at a like rate with the disintegrating mechanism, and that as the disintegrating mechanism is swung upwardly the pusher element will be further advanced and thus move the loose material in its path forwardly. The cumulative forward movement may be on the order of a yard for a dumping movement of eighteen inches, in a mine of substantial height.

In Fig. 11, there is shown in simple form a hydraulic system suited for the control of the apparatus for effecting clean-up of the mine floor. No effort has been made in this figure to show any more than will suffice to disclose the control of dumping and withdrawing, the supply and venting of fluid from the cylinder and piston mechanism 61, and the supply and venting of fluid from the upswing-effecting cylinder and piston devices 27.

The dumping and withdrawing cylinders, for effecting dumping and retraction of the disintegrating apparatus 11 and of the clean-up mechanism, are shown at 85, 85 in the diagram of Fig. 11, and one of them is also shown in part in Fig. 3. These are double acting cylinders, since they both advance and retract the disintegrating mechanism and the clean-up or pusher mechanism. They are connected together at their opposite ends by cross connections 86 and 87. A conduit 88 serves to supply fluid to the front ends of the cylinders 85 through the connection 87, and a conduit 89 serves to supply fluid to the rearward ends of the cylinders 85 through the cross connection 86. A connection 91 is adapted to supply fluid through branch connections 92, 92 to the upswing cylinders 27. A relief valve 93 is adapted, upon a development of excessive pressure within the cylinders 27—as, for example, in the event of a roof fall—to permit the venting of fluid through a relief connection 94 to a general return conduit 95, which leads from a valve box structure 96 and serves for the discharge of fluid from the valve box structure back to a tank or reservoir 98. A suitably driven pump 99 draws liquid from the reservoir 98 via a conduit 100 and delivers it through a conduit 101 to the supply box 102 of the valve box structure 96. The box section 104 of the valve box structure has the return line 95 connected to it, and a conduit 106 serves for the supply of fluid to a cylinder and piston mechanism 61, and for the venting of fluid from the latter.

Shown as parts of the valve box structure 96 are three valve units 108, 109 and 110. These are of conventional form and the first two simply control the supply of fluid to and the venting of fluid from the single acting cylinder and piston mechanism 61 and the pair of single acting cylinder and piston mechanisms 27. The unit 110 controls the supply of fluid selectively to the conduits 88 and 89, and the venting of fluid from these conduits. The structure of the units being conventional and being capable of side modification, it will suffice simply to mention that each has for its valve an operating stem, and that these stems are designated 111, 112 and 113 for the units 108, 109 and 110 respectively. It will be understood that when dumping is to be effected, the stem 113 will be operated to cause

the unit 110 to supply fluid to the conduit 89, while the conduit 88 is vented to the return line 95. When upswing is to be effected, the unit 109 will effect the supply of fluid to the conduit 91. When retraction is to be effected, conduit 89 will be vented and the conduit 88 supplied with fluid by the unit 110. During transport, the unit 108 will effect the supply of fluid to cylinder and piston mechanism 61. One more point might be mentioned; namely, that the supply box 102 is provided with a relief valve 115 and the units are so constructed as to permit free flow-through of pressure between the conduits 101 and 95 when none of the units 108, 109 and 110 is effecting fluid supply to the cylinder and piston mechanism which it controls.

No further detailed description of the structure or mode of operation of the invention appears to be necessary. Starting with the parts in the position shown in Fig. 10, the disintegrating mechanism and the pusher mechanism will be advanced to the right through the action of the dumping and withdrawing cylinders 85. The disintegrating mechanism will be then swung upwardly to the position shown at Fig. 9, and the pusher mechanism will be advanced to the position shown in that figure. The width of this mechanism will be made such that it will not interfere with any uncut portion of a face, or, if desired, it may be made narrow enough so that it lies wholly within the width of the disintegrating mechanism, with the result that there could be no interference with any uncut rib—whether a side rib or a rib bounding one of the vertical bands which are successively cut out. After the upswing disintegrating operation has been completed, the cylinders 85 will retract the whole apparatus, thus removing the relatively small ridge of coal at X in Fig. 9, and the pusher 71 being retracted from its extended position. The disintegrating apparatus will then be swung down, with simultaneous retraction of the pusher; and the disintegrating apparatus, as it reaches its lowered position, will clean up most of the material which lies beneath it as a result of a prior operation of the pusher mechanism during the removal of a previous vertical strip of coal across the face.

It will be evident that the apparatus is simple, effective, fully protected from self-damage, and automatic, or at least semi-automatic, in its operation.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim is:

1. In combination, a base, an elongated disintegrating apparatus, means swingably supporting said elongated disintegrating apparatus on said base for movement up and down in upright planes, a material pushing device, means supporting said material pushing device on said base for reciprocatory movement in the planes of swing of said disintegrating apparatus and in a path to which the swing of said disintegrating apparatus is transverse, and means controlled by the swing of said disintegrating apparatus and including mechanism connecting said apparatus and said device for transmitting movement from the former to the latter for retracting said device

as said disintegrating apparatus makes its down-swing.

2. In combination, a base, a carriage, reciprocably supported on said base, a disintegrating apparatus pivotally supported on said carriage for swinging movement upwardly and downwardly relative thereto in vertical planes, guideways on said carriage disposed substantially horizontal, a pusher element for moving material over a generally horizontal surface, said pusher element having supporting means slidably guided by said guideways, an arm connected with said disintegrating apparatus and swung as the latter moves upwardly and downwardly, a link pivotally connected to said slideable supporting means, and a pivotal connection between said link and said arm at a point in the latter offset from its axis of swing.

3. In combination, a frame, a disintegrating apparatus, means for pivotally supporting said disintegrating apparatus on said frame for swinging relative to the latter on a horizontal axis between lowered and raised positions, power means for swinging said disintegrating apparatus from said lowered to said raised position, guideways on said frame disposed generally horizontal, a pusher element guided by said guideways for moving material over a subjacent surface in a generally horizontal path relative to which said disintegrating apparatus is swingable vertically and into a portion of which said disintegrating apparatus is lowered by downward swing about said horizontal axis, and means for advancing said pusher element through said path and retracting it in synchronism with the swing of said disintegrating apparatus by forces derived from the movement of the latter and for preventing said pusher element and said disintegrating apparatus from being simultaneously in said portion of said path, said last mentioned means including mechanism energized by the swing of said disintegrating apparatus for reciprocating said pusher element.

4. The combination defined in claim 3 in which means is provided for pivotally supporting said guideways on said frame and in which there is further provided means for swinging said guideways angularly upwardly relative to said frame about their pivotal support on the latter.

5. The combination defined in claim 3 in which said mechanism energized by the swing of said disintegrating apparatus includes a link pivotally connected with said disintegrating apparatus at a point which lies beneath said horizontal axis when said disintegrating apparatus is in lowered position, and which link is pivotally connected with said pusher element.

6. In combination, a base, a disintegrating apparatus, means swingably supporting said disintegrating apparatus on said base for movement up and down relative to said base in upright planes, a material pushing device, means supporting said material pushing device on said base for horizontal movement relative to the latter, in the planes of swing of said disintegrating apparatus, over a subjacent level surface over which material is to be moved by said pushing device, and mechanism operatively connecting said disintegrating apparatus and said pushing device and actuated by said disintegrating apparatus during movement thereof for automatically advancing said device as said disintegrating apparatus is swung upwardly and for retracting said device as said disintegrating apparatus is swung downwardly and precluding the performance of

its respective movement by either said device or said apparatus while the other is stationary.

7. In combination, a base, a disintegrating apparatus swingably supported thereon for up and down movement in upright planes, a material pushing device, means including guides supported by said base guiding said pushing device for horizontal movement, in the planes of swing of said disintegrating apparatus, over a horizontal surface along which material is to be moved by said pushing device, and means including link means pivotally connected to one of the said disintegrating apparatus and said material pushing device and a pivot pin connected to the other thereof and to which said link means is pivotally connected, for automatically advancing said device horizontally as said disintegrating apparatus is swung upwardly and retracting said device as said disintegrating apparatus is swung downwardly.

8. In combination, a base, a disintegrating apparatus, means supported on said base pivotally supporting said disintegrating apparatus for movement in upright planes, a material pushing device, means supporting said material pushing device upon said base for movement in at least some of the planes of said disintegrating apparatus, said supporting means for said disintegrating apparatus and for said material pushing device supporting them, respectively for movement up and down and horizontally back and forth, in overlapping paths, and means for moving said disintegrating apparatus and said material pushing device so that each performs its function without interference with the other at the overlapping portion of said paths, said means including a push-pull connection for synchronizing the motion of said disintegrating apparatus and said material pushing device so that each moves away from the overlapping portion of said paths as the other moves towards such portion.

9. In combination, in a mining apparatus, a base, a carriage reciprocably supported on said base, a disintegrating apparatus pivotally supported on said carriage for swinging movement relative thereto in vertical planes, horizontal guideways on said carriage, a pusher element for moving material over a mine floor having supporting means slidably guided by said guideways, an arm movable with said disintegrating apparatus, a link pivotally connected to said slideable supporting means, a pivotal connection between said arm and link at a point below and at one side of the pivot of said disintegrating apparatus when the latter is in lowered position and below and at the other side of such pivot when said disintegrating apparatus is raised, and means for reciprocating said carriage.

10. In combination, in a mining apparatus, a base, a carriage reciprocably supported on said base, a disintegrating apparatus pivotally supported on said carriage for up and down swinging movement relative thereto in vertical planes, elongated horizontal guideways on said carriage, means for supporting said guideways for tilting adjustment about a horizontal axis relative to which said guideways extend substantially radially, means for adjusting said guideways about said horizontal axis, a pusher element having supporting means slidably guided by said guideways and movable back and forth to move material over a subjacent mine floor, an arm movable with said disintegrating apparatus, a link pivotally connected to said slideable supporting

11

means, and a pivotal connection between said arm and link.

11. In combination, a base, a disintegrating apparatus, means supporting said disintegrating apparatus on said base for swinging movement, including movement through a horizontal position, in upright planes, a material pushing device, means supporting said material pushing device upon said base for movement in the planes of swing of said disintegrating apparatus, in a path (a) offset vertically from said disintegrating apparatus when the latter is in a horizontal position and (b) substantially perpendicular to the instantaneous direction of movement of said disintegrating apparatus when the latter is passing through a horizontal position, and means for advancing said device as said disintegrating apparatus makes its swing in said upright planes away from the path of movement of said material pushing device and for retracting said device as said disintegrating apparatus makes its swing towards the path of movement of said material

5

20

12

pushing device, said means including mechanism converting the swinging motion of said disintegrating apparatus to a reciprocating motion and transmitting the latter to said material pushing device.
